UNITED STATES PATENT OFFICE.

FREDERICK WILLIAM MARGETTS, OF EAST DULWICH, ENGLAND, ASSIGNOR
OF ONE-HALF TO WILLIAM LANE MITCHELL AND CHARLES OLLIFFE,
OF EAST DULWICH GROVE, SURREY COUNTY, ENGLAND.

KNIFE-CLEANING APPARATUS.

SPECIFICATION forming part of Letters Patent No. 783,446, dated February 28, 1905.

Application filed January 7, 1904. Serial No. 188,059.

To all whom it may concern:

Be it known that I, FREDERICK WILLIAM MARGETTS, sanitary engineer, a subject of the King of Great Britain, residing at 11 Bawdale road, East Dulwich, in the county of Surrey, England, have invented certain new and useful Improvements in Machines for Scouring or Polishing Knives, of which the following is a specification.

10 My invention relates to knife-cleaning apparatus which is so constructed that a number of knives can be completely and thoroughly cleaned at one operation and without requiring to be shifted longitudinally in the apparatus. Furthermore, by my invention the knives are reciprocated in a straight line over fixed pads, thereby avoiding the production 15 on the blade of the curved marks usually produced when the knives are cleaned by rotating disk pads.

In the accompanying drawings, Figure 1 is a sectional elevation of a knife-cleaning apparatus constructed according to my invention. Fig. 2 is a plan of same. Fig. 3 is a section 25 taken on the line 3 3 of Fig. 1. Fig. 4 is an elevation showing a modification of the knife-holder and the lever mechanism for reciprocating it. Fig. 5 is a plan of part of Fig. 4, and Fig. 6 is a plan view of another modification 30 of the knife-holder.

The same letters of reference are used to denote the same or corresponding parts in all the figures.

A is an outer case or box having fitted in 35 the lower part thereof a pull-out drawer B, which forms a receptacle for the polishing-powder used during the cleaning. When convenient, the drawer B can be removed and the contents emptied into the polishing-powder 40 box C, which latter is provided with a trough-shaped mouth C', discharging into the interior of the apparatus between and above the polishing-pads. The polishing-pads are secured to suitable frames or backings D', mounted 45 on spiral or other springs D'' in the outer case or box A. The pads are arranged face to face in the ordinary way and are constructed alike. Each pad is made up of a series of parallel

strips of leather or other suitable material D³, arranged at an angle to the vertical, as shown 50 in Fig. 1, and the two pads, forming a pair, are arranged with the strips inclined in opposite directions. The strips D³ are left free at both ends and are secured in grooves or recesses D⁴, formed in the pad frame or backing D'. If desired, the strips D³ may be secured at the upper ends in longitudinal pieces 55 of the same material of a hardened character, fastened in any suitable manner to the pad frame or backing D'. At convenient places between the strips D³ bunches of bristles d³ or other suitable material are fixed to form ledges onto which the polishing-powder will fall and where it will be held during the 60 cleaning.

The knife-holder is in the form of a movable frame mounted on horizontal guide-rods E, on or fixed to the upper part of the outer case or box A. The knife-holder frame is made to clamp the knife-handles, being made with 70 one fixed and one movable part.

In the knife-holder shown in Figs. 1 and 2 one series of clamping-blocks, f, is secured to the fixed bar F of the knife-holder, the other series of clamping-blocks, f', being secured to the movable bar F', which latter is secured to a bracket F'', having a threaded aperture therethrough in which engages the screw-bolt G, mounted in the bearing G' and operated by a suitable handle G''. 75

In the modification shown in Fig. 6 the clamping-blocks are kept in the closed position by means of the spring H, which bears on the bracket F'' and bearing G'. The blocks are opened by means of a cam-lever J on the 85 rod K, which latter is secured to the bracket F'', said cam-lever taking against the outside of bearing G'.

In the modification shown in Figs. 4 and 5 a knife-holder adapted to receive one knife 90 only is shown. In this form the movable bar F', carrying the movable clamping-block f', is mounted on the top of two fixed bars F instead of to one side. Otherwise this modification is constructed and operated in the same 95 way as that shown in Fig. 6.

It will be observed that in all the forms of the knife-holder the clamps are arranged so as to hold the knife-handle fore and aft relatively to the direction of travel of the holder, 5 so that there is no risk of the knife being left behind when the knife-holder is reciprocated.

The knife-holder frame is reciprocated on the horizontal guide-rods E by lever mechanism connected to a fixed center of motion N on 10 the side of the outer case or box A. In Fig. 1 the reciprocation is effected by the connecting-rod L and crank M, operated by the crank-handle m. In Fig. 4 a slotted lever P is employed, having an operating-handle p, this being sufficient 15 where the travel is short; but any other suitable arrangement of levers may be used for effecting the desired reciprocating straight-line movement of the knife-holder.

Having fully described my invention, what 20 I claim, and desire to secure by Letters Patent, is—

1. A knife scouring or polishing machine comprising an outer frame or box, two vertical resiliently-mounted polishing-pads arranged 25 face to face, a frame therefor, guide-rods mounted on the outer frame, a knife-clamping frame mounted for reciprocation upon the said guide-rods, and means for reciprocating the knife-clamping frame comprising 30 lever mechanism attached to the clamping-frame and turning on a fixed center on the said outer frame or box.

2. A knife scouring or polishing machine

comprising an outer frame or box, two polishing-pads arranged vertically and face to face, 35 each pad being composed of leather strips arranged parallel and at an angle to the vertical and a backing to which the strips are secured, springs bearing upon the backings of the pads so as to make the latter yielding, guide-rods 40 mounted on the outer frame, a knife-clamping frame mounted for reciprocation on the guide-rods, and means for reciprocating the knife-clamping frame.

3. A knife scouring or polishing machine 45 comprising an outer frame or box, two vertical resiliently-mounted polishing-pads arranged face to face, a frame therefor, guide-rods mounted on the outer frame, a knife-clamping frame mounted for reciprocation 50 upon the said guide-rods, said clamping-frame comprising a fixed and a movable part, a series of clamping-blocks secured to the fixed part, a second series of clamping-blocks secured to the movable part, a bracket to which the movable 55 part is secured, a screw-bolt working in said bracket, said screw-bolt having an operating-handle.

In testimony whereof I have hereunto set my hand, in presence of two subscribing witnesses, this 22d day of December, 1903.

FREDERICK WILLIAM MARGETTS.
